DESIGN FOR A DISPLAY DEVICE

Frank Springer-Miller, Stowe, Vt., assignor to
Salers, Inc., New York, N. Y., a corporation of
New York

Application November 24, 1948, Serial No. 149,805

Term of patent 14 years

(Cl. D80—9)

To all whom it may concern:

Be it known that I, Frank Springer-Miller, a citizen of the United States of America, residing at Stowe, county of Lamoille, State of Vermont, have invented a new, original, and ornamental Design for a Display Device, of which the following is a specification, reference being had to the accompanying drawing, forming part thereof.

In the drawing:

Fig. 1 is a front elevational view of a display device, showing my new design.

Fig. 2 is a side elevational view; and

Fig. 3 is a plan view.

I claim:

The ornamental design for a display device, as shown.

FRANK SPRINGER-MILLER.
